US00D654491S

(12) **United States Design Patent**
Melanson et al.

(10) **Patent No.:** **US D654,491 S**
(45) **Date of Patent:** **** Feb. 21, 2012**

(54) **CASE FOR ELECTRONIC DEVICE**

(75) Inventors: **Christopher Melanson**, Fort Collins, CO (US); **Cameron Magness**, Fort Collins, CO (US)

(73) Assignee: **Otter Products, LLC**, Fort Collins, CO (US)

(**) Term: **14 Years**

(21) Appl. No.: **29/402,646**

(22) Filed: **Sep. 26, 2011**

(51) **LOC (9) Cl.** **14-03**

(52) **U.S. Cl.** **D14/250**

(58) **Field of Classification Search** D14/250-253, D14/440, 203.3-203.7, 217, 496, 248, 238.1; D3/201, 218, 269, 301, 273, 303; D13/103, D13/107-108; 220/4.02; 248/309.1; 361/679.56; 379/426, 433.11, 455; 455/575.1, 575.8; 190/100; 206/305, 320

(57) **CLAIM**

The ornamental design for a case for electronic device, as shown and described.

DESCRIPTION

FIG. 1 is a front isometric view of a case for electronic device showing our new design;

FIG. 2 is a rear isometric view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines immediately adjacent the claimed surfaces represent boundaries of the claimed design. All other broken lines depict unclaimed environment. The broken lines form no part of the claimed design.

1 Claim, 6 Drawing Sheets

FIG. 1

FIG. 2

FIG. 3

FIG. 4

FIG. 5

FIG. 6

FIG. 7

FIG. 8
